UNITED STATES PATENT OFFICE.

JOHN DOUGLASS GRANGE, OF BROOKFIELD, AND MARION LLEWELLYN STRAWN, OF LA GRANGE, ILLINOIS, ASSIGNEES TO WESTERN ELECTRIC COMPANY, INCORPORATED, OF NEW YORK, N. Y., A CORPORATION OF NEW YORK.

COMPOSITE ARTICLE.

Application filed October 7, 1924. Serial No. 742,130.

This invention relates to composite articles, and more particularly to stencil units.

In employing stencil blanks of the class wherein filling material impervious to ink is expressed from a tissue sheet in response to the action of a typewriter, in some instances a so-called backing sheet is placed between the stencil blank and the platen of the typewriting machine. This backing sheet serves to prevent the severing of the fibers of the stencil blank when the blank is being cut or stenciled by the typewriting machine. To facilitate the use of such stencil blanks it is desirable to assemble the blanks and the backing sheets into integral units, ready for insertion in the machine.

An object of the invention is to provide an improved composite article.

In order to attain this object in accordance with the features of the invention there is provided a composite article having cooperating portions self-attached to each other, such article comprising a portion having a non-adhesive coating and another portion having an ingredient which may be converted into an adhesive. In one specific embodiment of the invention the stencil blank, which may have a water soluble gelatinous base such as that described and claimed in Patent 1,562,228, issued to J. D. Grange, November 17, 1925, is assembled with a backing sheet. The backing sheet may have a waxy or paraffin surface for direct contact with one surface of the blank, such surface serving to preserve the blank during storage, as well as performing the usual functions of a backing sheet. Such sheet may be of the type described and claimed in Patent 1,562,228, issued to J. D. Grange, November 17, 1925. The stencil blank is self-attached to the backing sheet preferably by following the method and using the apparatus described in our copending application, Serial No. 742,129, filed October 7, 1924, wherein a portion of the backing sheet is heated to prepare the surface thereof to receive an adhesive by causing the coating to be ab-

sorbed by the body portion of the sheet, thus leaving the surface of the portion substantially free of the coating. Moisture and pressure is then applied to a portion of the stencil blank which has been placed upon the prepared portion of the backing sheet, the moisture softening the gelatine in the stencil blank so that it forms an adhesive and the pressure causes the adhesive to firmly unite the stencil blank and the prepared portion of the backing sheet.

Other objects and advantages of the invention will more fully appear from the following detailed description taken in connection with the accompanying drawings which illustrate one embodiment of the composite article, and in which

Fig. 1 is a front elevation of a complete stencil unit, and

Fig. 2 is an enlarged cross-section of the unit shown in Fig. 1.

Referring now to the drawings in detail in which like reference numerals designate similar parts throughout the several views, 10 denotes a backing sheet of fibrous material of the type disclosed and claimed in the copending application of J. D. Grange, Serial No. 742,103, filed October 7, 1924, 75 and 11 an associated stencil blank, which may have a water soluble gelatinous base, such as that described and claimed in the copending application of J. D. Grange, Serial No. 630,125, filed November 24, 1922. 80

The backing sheet 10 is provided with a plurality of usual perforations or slots 13 which facilitate the attachment of the stenciling material or unit to a machine for reproducing the stenciled characters. One 85 side of the backing sheet 10 is covered with an unbroken coating 12 (Fig. 2) of a non-hygroscopic and non-adhesive substance, such as paraffin or wax, which coating may be applied in any usual manner. The coating 12 covers all of the fibers of the side of the backing sheet 10 adjacent to the under surface of the stencil blank 11 and is in direct contact with such surface. The thick-

ness of the coating is such that it will prevent exposure of any fiber of the backing sheet during the stencilization of the blank.

The stencil blank 11 may be self-attached to the backing sheet 10, preferably by employing the method and apparatus disclosed and claimed in our copending application, Serial No. 742,129, filed October 7, 1924, wherein a restricted portion of the backing sheet is heated to prepare the surface thereof to receive an adhesive by causing the coating to be absorbed by the body portion of the sheet, thus leaving the surface of the portion substantially free of the wax or paraffin. Moisture and pressure are then applied to a portion of the stencil blank in contact with the prepared portion of the backing sheet. The moisture softens the gelatinous base of the stencil blank so that it forms an adhesive and the pressure causes the adhesive to firmly unite the stencil blank and the prepared portion of the backing sheet, as shown at point 15 in Fig. 1.

It is, of course, to be understood that the coating of paraffin is non-hygrosopic and impervious to water, and hence will prevent the backing sheet from absorbing the essential moisture in the stencil blank and thus preserves the blank ready for immediate stencilization, as well as protects the fibrous material of the sheet from the moistening fluid used during the stencilization. This is very important, inasmuch as it prevents the fibers of the backing sheet from absorbing moisture, thereby insuring that the characters being cut in the stencil are accurately and sharply defined.

A stencil unit embodying this invention is of simple construction, of a minimum number of co-acting members, and may be stored for long periods of time and in a minimum amount of space. When these units are packed in pairs with the blanks thereof in contact, the paraffin coating of the backing sheet not only serves to effectively prevent the escape, by evaporation, of the essential moisture in the stencil blank, but also to protect the blank from any excess moisture in the storage atmosphere; thus the stencil blanks are maintained in condition for immediate stenciling throughout long periods of storage.

What is claimed is:

1. A composite article comprising a waxy coated backing member having a portion of its surface prepared for an adhesive, and a second member attached to the prepared surface of the first member, said second member having a bonding ingredient which is rendered adhesive by moisture.

2. A composite article comprising a backing member having a portion of its surface covered with a non-adhesive, impressionable substance and a portion of said surface capable of accommodating an adhesive,

and a member attached to the latter mentioned portion by an adhesive formed from an ingredient contained in the second mentioned member.

3. A composite article comprising a member having an impressionable coating which has a portion of its surface prepared for an adhesive, and a second member attached to the prepared surface of the first member, said second member having a gelatinous ingredient which is rendered adhesive by moisture.

4. A composite article comprising a paraffin coated member which has a portion thereof free from the paraffin and is in condition to accommodate an adhesive, and a second member attached to the paraffin free surface of the first mentioned member, said second member having a bonding ingredient which is rendered adhesive by moisture.

5. A stencil unit comprising a paraffin coated backing sheet having a portion thereof prepared for an adhesive and a stencil sheet attached to the prepared portion of the backing sheet, said stencil sheet having a bonding ingredient of gelatin.

6. A stencil unit comprising a paraffin coated backing sheet of fibrous material having a portion thereof prepared for an adhesive, and a stencil blank attached to the prepared portion having a gelatinous base adapted to be rendered adhesive.

7. A stencil unit comprising a paraffin coated backing sheet and a stencil blank in direct contact with the coating and attached to the backing sheet by an ingredient of said stencil blank.

8. A stencil unit comprising a paraffin coated backing sheet and a stencil blank in direct contact with the coating and attached to the backing sheet by a water soluble gelatinous base contained in said stencil blank.

9. A stencil unit comprising a paraffin coated backing sheet and a stencil blank in direct contact with the coating and attached to the backing sheet, said stencil blank having an ingredient which is rendered adhesive by moisture.

10. A stencil unit comprising a paraffin coated backing sheet having a portion of its surface prepared for an adhesive, and a stencil blank attached to the prepared surface of said backing sheet by an adhesive ingredient contained in said blank.

11. A stencil unit comprising a paraffin coated backing sheet having a portion of its surface prepared for an adhesive, and a stencil blank attached to the prepared surface, said stencil blank having a water soluble gelatinous base which is rendered adhesive by moisture.

12. A stencil unit comprising a paraffin coated backing sheet which has a portion of its surface prepared for an adhesive, and

a stencil blank adhering at one end to the prepared surface of the backing sheet.

13. A stencil unit comprising a paraffin coated backing sheet which has a portion of its coated surface prepared for an adhesive, and a stencil blank adhering at one end to the prepared surface of the backing sheet

by an adhesive ingredient contained in said blank.

In witness whereof, we hereunto subscribe our names this 27th day of September A. D., 1924.

JOHN DOUGLASS GRANGE.
MARION LLEWELLYN STRAWN.
